US00D803238S

(12) **United States Design Patent** (10) **Patent No.:** **US D803,238 S**
Anzures et al. (45) **Date of Patent:** **** Nov. 21, 2017**

(54) **DISPLAY SCREEN OR PORTION THEREOF WITH GRAPHICAL USER INTERFACE**

(71) Applicant: **Apple Inc.**, Cupertino, CA (US)

(72) Inventors: **Freddy Anzures**, San Francisco, CA (US); **Imran Chaudhri**, San Francisco, CA (US); **Alan C. Dye**, San Francisco, CA (US); **Bradley William Griffin**, Berkeley, CA (US); **Jonathan P. Ive**, San Francisco, CA (US); **Tiffany Jon**, Sunnyvale, CA (US); **Chanaka Karunamuni**, Cupertino, CA (US); **Nicholas V. King**, San Jose, CA (US); **Daamun Mohseni**, San Jose, CA (US); **Hoan K. Pham**, San Jose, CA (US); **William McMillan Tyler**, San Francisco, CA (US); **Wan Si Wan**, Sunnyvale, CA (US); **Giancarlo Yerkes**, Menlo Park, CA (US)

(73) Assignee: **Apple Inc.**, Cupertino, CA (US)

(**) Term: **15 Years**

(21) Appl. No.: **29/567,745**

(22) Filed: **Jun. 12, 2016**

(51) LOC (10) Cl. **14-04**

(52) U.S. Cl.

USPC **D14/485**

(58) **Field of Classification Search**

USPC D14/485-495

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet
